UNITED STATES PATENT OFFICE.

CLARENCE C. COUSINS, OF ALTON, ILLINOIS, ASSIGNOR OF ONE-THIRD TO ANNIE COUSINS, OF ALTON, ILLINOIS.

SAFETY VALVE FOR THE TRAIN LINES OF AIR-BRAKE SYSTEMS.

Application filed March 10, 1927. Serial No. 174,282.

The invention relates to safety devices for railroad trains designed to set the brakes on the train when any one of the trucks on the train leaves the track, and has for its 5 object the provision of a valve communicating with the train line and arranged between the wheels of the truck, that is opened by engagement with the railroad rail to bleed the train line of pressure and set the brakes on 10 the train to automatically stop the train should the wheels leave the track.

A further object of the invention is the provision of a safety valve comprising a casing adapted to be secured to a branch line 15 connected with the train line of an air brake system and having a plunger therein that is normally moved into closed position by means of an expansible coil spring and provided with a stem extending through the 20 bottom of the casing on which is mounted an elongated plate that is arranged immediately above the rail between the wheels of the train truck, and adapted to engage the rail when the wheels leave the track to move the plunger 25 and stem inwardly of the casing, the stem being provided with grooves forming ports for outlet of pressure in the train line, the plate also being provided with openings communicating with said grooves to insure 30 bleeding the train line in whatever position may be assumed by the stem and plate relatively to the casing.

The invention will be described in detail hereinafter and will be found illustrated in 35 the accompanying drawings, in which

Figure 1 is a side view of a fragment of a railroad coach showing the wheeled truck and train line with the improved safety valve positioned for operation,

Figure 2 is a view of the valve, on an enlarged scale, showing the valve casing in 40 section,

Figure 3 is a sectional detail of the lower end of the valve casing and valve plunger 45 and stem, and

Figure 4 is a transverse sectional view on a plane indicated by the line 4-4 of Figure 2.

In the drawings similar reference characters will be used to designate corresponding parts throughout the several views.

In Figure 1 a wheeled truck is suggested at A having the wheels B, supporting the base of a car C and mounted on the rail D, E indicating the train line of an air brake

system, to which is connected a branch line F having secured thereto the valve casing 1 by means of a nipple 2. The valve casing comprises two members 3 and 4 that threadedly engage one another as shown at 5, the 60 nipple 2 being connected with the member 3. 6 designates spaced segmental bearings secured to the walls of the portion 4, or formed integral therewith, by means of arms 7, the segmental bearings 6 being spaced from 65 the walls to provide openings 8 to connect the upper and the lower parts of the casing when the valve is operated as will be hereinafter described.

A plunger 9 is slidably mounted in the 70 bearings 6, and is normally held in a lowered position, by means of the expansible coil spring 10, 11 indicating an extension on the plunger 9 to form a seat for the lower end of the spring 10, and 12 a sleeve mounted in 75 the lower portion of the nipple 2 to form a seat for the upper end of the spring. The upper end of the extension 11 is tapered as shown at 13 and provided with grooves 14 to permit escape of air from the branch F 80 into the casing should the tapered end extend into the bore of the sleeve 12 in operating the plunger 9 by the means hereinafter described.

Stem 15 extends from the lower portion 85 of the plunger 9 to an opening 16 in the lower portion of the section 4 of the casing 1, and is provided with longitudinal grooves 17 and has secured thereto a plate 18 having openings 19 communicating with said grooves 90 17. Stem 15 is provided with a circumferential flange 20 spaced from the lower side of the plunger 9 to form a recess in which is mounted a gasket or packing 21 that makes an air tight joint between the plunger 9 and 95 the lower portion of the section 4 when the plunger is in its lowermost position as shown in Figure 2.

In operation, it will be apparent that when the parts are in the position shown in Figure 2 pressure in the train line will be maintained. Should, however, one of the trucks leave the track, the plate 18 will engage the track and move the parts into the position shown in Figure 3 and thus move the stem 100 15 so that the grooves 17 form ports connected with the interior of the casing 1 and the pressure in the train line will be reduced to automatically set the brakes and prevent 105 operation of the train. By this means it will 110

2
be apparent that the operation of the brakes to set them is automatic, and provision is made by which dragging of the derailed truck over the ties thus damaging the road bed, and at the same time endangering wrecking the train will be avoided.

What is claimed is:—

1. An emergency valve for air brakes, comprising a casing, a spring actuated plunger in said casing, a stem on said plunger provided with grooves, and a plate on said stem and having openings therein communicating with said grooves, said casing being adapted to be mounted between 10 the wheels of a car truck and connected with the train line of an air brake system.
2. An emergency valve for air brakes, comprising a casing, bearings in said casing spaced from the walls thereof, a plunger 20 supported by said bearings, a stem on the plunger extending through an opening in the casing and having grooves therein forming ports communicating with the interior of the casing in some positions of the plunger, and a plate on said stem and having openings therein communicating with said grooves, a flange on the stem, and packing on the stem between the flange and plunger, said casing being adapted to be mounted between the wheels 25 of a car truck and connected with the train line of an air brake system.

ing openings therein communicating with said grooves, said casing being adapted to be mounted between the wheels of a car truck and connected with the train line of an air brake system.

3. An emergency valve for air brakes, comprising a casing, segmental bearings in said casing spaced from the walls thereof, a spring actuated plunger slidably engaging said bearings, a stem on the plunger extending through an opening in the casing and having grooves therein forming ports communicating with the interior of the casing in some positions of the plunger, a plate on said stem and having openings therein communicating with said grooves, a flange on the stem, and packing on the stem between the flange and plunger, said casing being adapted to be mounted between the wheels of a car truck and connected with the train line of an air brake system.

In testimony whereof I affix my signature.

CLARENCE C. COUSINS.
